Specification for Design.

Patented Dec. 28, 1920.

Application filed July 8, 1920. Serial No. 394,836. Term of patent 3½ years.

To all whom it may concern:

Be it known that we, HARRY C. AATHERLEY and JAMES E. AATHERLEY, both citizens of the United States, and residents of the city and county of San Francisco and State of California, have invented a new, original, and ornamental Design for a Lamp-Stand, of which the following is a specification, reference being had to the accompanying drawings, forming a part thereof.

In the drawing:

Fig. 2 is a side elevation of the lamp stand.

What we claim is:

The ornamental design for a lamp stand substantially as shown.

In testimony whereof, we have hereunto set our hands this 29th day of June, 1920, in the presence of the two subscribed witnesses.

HARRY C. AATHERLEY.
JAMES E. AATHERLEY.
